UNITED STATES PATENT OFFICE

ALDER F. CONNERY, OF BROOKLYN, NEW YORK, ASSIGNOR TO POSTAL TELEGRAPH
CABLE COMPANY, OF NEW YORK, N. Y., A CORPORATION OF CONNECTICUT

TELEGRAPH SYSTEM

Application filed January 18, 1928. Serial No. 247,493.

This invention relates to telegraph systems and particularly to a telegraph system in which transmission of signals in one direction is effected by reversing the polarity of the line current, and in the other direction by making and breaking the line circuit.

It is often desired to install a telegraph circuit between a central telegraph office and a small telegraph office located at a point 50 to 100 miles distant. The closed circuit Morse system of telegraphy which only requires a line relay, sounder and key at each station may be used for this purpose, but it is objectionable in that it is necessary to adjust the line relay at each station to compensate for changes in line conditions due to leakage and other causes. The operator at the central office is usually experienced and has no difficulty in keeping the relay in adjustment, but the operator at the small office may be unable to keep the relay properly adjusted, and this is particularly true when complicated printing telegraph apparatus is used because it is very difficult to distinguish between the errors caused by improper line relay adjustments and those caused by improper adjustment of the printing telegraph apparatus itself.

The use of a double current non-duplex system eliminates the need of adjustments to compensate for variation in line conditions, but the objection is that both positive and negative poles of line battery must be available at both terminals and furthermore it is necessary to operate switches each time a change is made from sending to receiving conditions and vice-versa. A further objection is that while one station is sending it is not possible for the other station to "break" the sender.

The principal object of this invention is to provide a telegraph system, suitable for the accurate transmission of messages over a line conductor in either direction, which requires no adjustments to compensate for

change in line conditions to be made at one of the stations and furthermore requires no line current supply at the station at which no adjustments are required.

Other objects and advantages of the invention will be set forth in detail in the following specification, and particularly pointed out in the appended claims.

In the accompanying drawings,

Fig. 1 is a schematic diagram of an embodiment of this invention as used for communication between a main telegraph office and a single branch office. 55

Fig. 2 is a schematic diagram of an embodiment of this invention as used for communication between a main telegraph office and a plurality of branch offices. 60

In the drawings like parts are represented by like numerals.

Referring to Fig. 1, the central telegraph office is shown in the part of the drawing marked A and the branch telegraph office is shown at B. The two offices are connected together by line conductor L. 65

The transmission from the central office is effected by operating key 1 which is kept short circuited when not in use by short circuiting switch 2. Key 1 operates pole-changer relay 3. The front and back contacts of polechanger 3 are connected to grounded sources of current of substantially equal voltage but of opposite polarity. The tongue 15 of polechanger 3 is connected to the mid-point of differentially wound polarized relay 4. The current from the pole-changer splits at relay 4 so that part of it goes through one winding of relay 4, line L, polarized relay 5 at the branch telegraph office and thence to ground while the remainder goes through the other winding of relay 4 and through variable resistance 6 to ground. The value of resistance 6 is normally adjusted so the current flowing through it is approximately one-half the value of the line current. The relay 4 responds to the 70

80

85

90

polarity of the difference of the currents in its two windings. The connections to the relays are such that, when neither station is sending, the tongue 7 of relay 4 has closed the circuit to sounder 8 and tongue 9 of relay 5 has closed the circuit to sounder 14. The retractile spring 10, which is attached to armature 9, tends to move the armature 9 away from contact 11. The pull of the retractile spring 10 is small as compared to the force normally exerted on the armature by the line current. The purpose of this spring is explained in another part of this specification. Each signal sent from station A, reverses the polarity of the line current which energizes relays 4 and 5 which respond and operate the sounders connected to them. In the case of station A transmitting, the object of operating sounder 8 is to produce a home record of the sent signals. The signals are read from sounder 14 at station B. In this case it is apparent that a reasonable amount of leakage will have no disturbing effect on the operation of relays 4 or 5 since they are, in this case, responsive to the polarity of the signal rather than the current strength.

Station B transmits by manipulating key 12 which is short-circuited, when not in use, by switch 13. Operation of key 12 opens and closes the line circuit. Relay 5 responds to this opening and closing of the line circuit because, during the period that the line is open, the spring 10 pulls the armature 9 away from contact 11. In this manner the home record of sending at station B is produced. The manipulation of key 12 also operates relay 4 at station A because when the current in the line coil is interrupted or reduced the current in the other winding, the value of which is regulated by resistance 6, controls the relay and thereby operates sounder 8.

Fig. 2 shows how this invention may be used in connection with a main telegraph office and a plurality of branch telegraph offices. In the drawing only two branch offices are shown but it should be understood that this number may be increased when desired. The two branch offices are shown in the parts of the drawing marked B and C. The B station is identical with the B station shown on Fig. 1. The C station is similar to B except that the line circuit, instead of being grounded, is carried on to station B.

The signals sent from station A are received at stations B and C and signals sent from stations B or C are received at station A. Stations B and C cannot, however, reliably communicate with each other because the biasing spring 10 and 15 on their relays is of insufficient strength to overcome line induction when the line circuit is opened at a distant station.

It will be apparent from the foregoing de-

scription that a telegraph system embodying this invention is suitable for use between a main telegraph office and one or more branch offices and that only one adjustment is required to compensate for a change in line conditions and this adjustment is made at the main office.

Although the invention has been disclosed and described in conjunction with the Morse system of telegraphy it should be obvious that it is suitable for use in connection with a printing telegraph system and it may also be used in connection with other means of transmitting intelligence without departing from the spirit and scope of the present invention.

I claim:

1. In a telegraph system, a main station, a branch station, a line circuit connecting said stations, polechanger transmitting means at said main station, polarized receiving means at said branch station responsive to signals transmitted from either of said stations, make and break transmitting means at said branch station, double-wound polarized receiving means at said main station responsive to signals transmitted from either of said stations, one of said windings being connected in series with said line circuit and the other winding being in series with a variable resistance, said variable resistance being for the purpose of adjusting the receiving means at said main station to respond to signals transmitted from said branch station, despite variation in electrical conditions of said line circuit.

2. In a telegraph system, a main station, a branch station, a line connection between said stations, polechanger transmitting means at said main station, polarized receiving means at said branch station responsive to signals transmitted from either of said stations, make and break transmitting means at said branch station, double-wound polarized receiving means at said main station responsive to signals transmitted from either of said stations, said windings being connected in opposition to each other, the first of said windings being connected in series with said line circuit and the second of said windings being connected to ground, means for varying the relative magnetic strength of the said windings, the direction of current through each of said windings being controlled by the transmitting means at the said main station.

3. In a telegraph system, a main station, one or more branch stations, a series connected line circuit between said stations, polechanger transmitting means at said main station, polarized receiving means at each of said branch stations responsive to signals transmitted from the home station as well as from the said main station, make and break transmitting means at said branch stations, double-wound polarized receiving means at said main station responsive to signals trans-

mitted from either of said stations, one of said windings being connected in series with said line circuit and the other winding being in series with a variable resistance, said variable 5 resistance being for the purpose of adjusting the receiving means at said main station to respond to signals transmitted from any of said branch stations despite variation in electrical conditions of said line circuit.

10 4. In a telegraph system, a main station, one or more branch stations, a series connected line circuit between said stations, pole-changer transmitting means at said main station, polarized receiving means at each of 15 said branch stations responsive to signals transmitted from the home station as well as from the said main station, make and break transmitting means at said branch station, double-wound polarized receiving means at 20 said main station responsive to signals transmitted from any of said stations, said windings being connected in opposition to each other, the first of said windings being connected in series with said line circuit and the 25 second of said windings being connected to ground, means for varying the relative magnetic strength of the said windings, the direction of current through each of said windings being controlled by the transmitting 30 means at said main station.

5. In a telegraph system, a main station and one or more branch stations in a series circuit, a single source of current at the main station supplying the entire line current, 35 transmitting means at the main station adapted to reverse the polarity of current supplied from said source, transmitting means at a branch circuit adapted to open and close the line circuit, and relay means 40 at each station responsive to both transmitting means.

6. A telegraph system comprising a main station having a polar differential receiving relay, an outgoing line circuit one side of 45 which is connected to one arm of said relay, a resistance greater than said line resistance connected between the other arm of said relay and the other side of said line circuit, a current source at the main station for supplying 50 all the line current for the entire line, a transmitting device comprising means for connecting said source between the mid tap of said relay and the other side of said line circuit and for reversing the polarity thereof 55 to transmit signals, and one or more branch stations connected in series in said line circuit, each branch station comprising a biased polar receiving relay and a transmitting key connected in series in said line circuit.

60 7. In a telegraph system, a main station, one or more branch stations, a series connected line between said stations, one of said stations furnishing line potential for all of 65 said stations, pole changer transmitting means at said main station, polarized receiv-

ing means responsive to signals transmitted from the home station as well as from the said main station, make and break transmitting means at said branch station, double-wound polarized receiving means at said 70 main station responsive to signals transmitted from any of said stations, said windings being connected in opposition to each other, the first of said windings being connected in series with said line circuit and the 75 second of said windings being connected to ground, means for varying the relative magnetic strength of the said windings, the direction of current through each of said windings being controlled by the transmitting 80 means at said main station.
